UNITED STATES PATENT OFFICE.

MAXIME VALLÉE, OF ST. JEROME, CANADA.

LOCK-LATCH.

SPECIFICATION forming part of Letters Patent No. 719,705, dated February 3, 1903.

Application filed March 26, 1902. Serial No. 100,046. (No model.)

To all whom it may concern:

Be it known that I, MAXIME VALLÉE, a subject of the King of Great Britain, residing at St. Jerome, county of Terrebonne, Province of Quebec, Canada, have invented certain new and useful Improvements in Lock-Latches; and I do hereby declare that the following is a full, clear, and exact description of the invention, such as will enable others skilled in the art to which it appertains to make and use the same.

My invention relates to an improved door-fastening which is in the nature of a combined latch and lock—that is to say, the metal tongue which forms the latch is adapted to be reciprocated and to be pushed into a socket, so that it also forms the bolt of a lock.

The object of my invention is to provide a fastening which shall dispense with unnecessary parts and utilize the latch-tongue simultaneously as a lock-bolt in the manner above referred to and to provide means whereby a single handle can be operated in connection with the key placed therein to withdraw the bolt of the lock and by the same operation raise the tongue of the latch.

In my improved construction I provide a metal casing or box containing a metallic tongue or bolt having a rectangular slotted extension cast integral therewith and having lugs or flanges thereon which engage with the sides of an eccentric mounted on a rotatable handle-spindle in such manner that the rotation of the handle will cause the said metallic tongue to reciprocate, and I further provide means whereby the rotatable handle at one point of its revolution catches in the projecting metallic tongue and turns it about its own axis in the manner of a latch.

An important feature of my invention consists in the manner in which the said engagement between the rotatable handle-spindle and latch-piece is caused to take place. The eccentric mounted upon the handle has a notch in its periphery, in which engages a spring-pressed tongue carried by the slotted frame of the bolt or latch-tongue, so that when this pin is engaged with the eccentric the two will move solidly as one piece.

The most essential feature of my invention, however, lies, perhaps, in the manner in which the disengagement of the spring-

pressed tongue from the eccentric is brought about, and this consists in a small slideable releasing-bolt which is operated by a barrel-lock inserted into the interior of the rotatable handle-spindle, which is made in the form of a hollow barrel for this purpose.

As a special modification adapted for heavy doors where locks are required to be much heavier than the fastening-latches I provide three or more bolts, each of which is adapted to engage in a suitable socket in the door-frame, but only one of which is adapted to act as a latch, and to this end the latch-bolt is mounted in the same manner as in the case where it is used alone; but the rectangular extension which it carries is provided with means for engaging with a frame on which the remaining bolts are mounted, so that the rotation of the latch-bolt as a latch will have no effect upon the other bolts; but its reciprocation as a lock will cause them to be reciprocated simultaneously with it to be drawn or shot.

My invention further consists in the peculiar construction and combination of parts which will be hereinafter described, and particularly pointed out in the claims.

I have illustrated my combination lock-latch in the accompanying drawings, wherein—

Figure 1 is a perspective view of the ordinary form of my lock-latch as attached to a door. Fig. 2 is a vertical longitudinal section taken through the device shown in Fig. 1 just beneath the outer face of the casing or box and showing the latch-tongue shot to act as a lock. Fig. 3 is a similar view to Fig. 2, but showing the application of a key in the process of unlocking the latch-tongue to draw the same into retracted position. Fig. 4 is a similar view to Fig. 3, but showing the latch-tongue as withdrawn and the parts in position to be turned as a latch. Fig. 5 is a vertical transverse section through the axis of the hollow spindle. Fig. 6 is a detailed perspective view of the casing. Fig. 7 is a similar view of the cover-plate therefor. Fig. 8 is a similar view of the hollow spindle carrying the eccentric sheave. Fig. 9 is a similar view of the latch-tongue and the slotted frame forming a part thereof. Fig. 10 is a similar view of the catch-piece. Fig.

11 is a similar view of the parts constituting the locking mechanism, the several parts being shown in separated positions in order to more clearly illustrate their formation and 5 mode of combination. Fig. 12 is a perspective view of a key adapted to operate the lock-barrel. Fig. 13 is a longitudinal section taken just beneath the face-plate of a modified form of my improved lock-latch especially 10 adapted to heavy doors and showing the same in locked position. Fig. 14 is a similar view to Fig. 13, showing the fastening in unlocked position; and Fig. 15 is a central longitudinal section of a slightly-modified form 15 of locking-barrel.

The same numerals of reference denote like parts in all the figures of the drawings.

Referring first to the form of lock shown in Figs. 1 to 5, inclusive, 16 designates the 20 casing or box of the fastening, this box having a cover-plate 17 on the back thereof, to which it is attached by means which will be hereinafter referred to. The box or casing is of an approximately rectangular form, 25 being formed, as in the drawings, with its upper and lower sides 18 and the free side 19 opposite to the locking-face of the fastening slightly concave for ornamental purposes, and through the casing and its cover are formed 30 holes in the four corners thereof, through which are inserted screws or like fastenings 20 for attaching the lock-latch to the door 15. In the center of the box 16 is also formed a transverse circular aperture 21 of sufficient 35 size for the insertion of the hollow handle-spindle 22, and the cover-plate 17 is formed with a similarly-formed aperture 23 for the same purpose. The hollow spindle 22 carries fixed thereto an eccentric sheave 24, the throw of 40 which—that is to say, the double distance of its center from the center of the handle-spindle—is equal to the throw of the latch-tongue in the locking operation, and in the edge of the sheave 24, diametrically opposite the handle-spindle, is formed a square transverse 45 notch 25. The eccentric sheave when the lock is in place is located at the bottom of the box 16—that is to say, at the front portion thereof—and engages with the latch-piece to reciprocate and oscillate the same in 50 a manner which will be presently described.

The latch-piece proper (designated as a whole by 26) is shown by itself in detail view in Fig. 9, and it consists of an outwardly-extending latch-tongue 27, which is destined to 55 perform the simultaneous function of a locking-bolt, as will hereinafter be shown, and of a rectangular extension or frame 28, which is centrally slotted, as shown at 29, the ends of 60 the slot 29 being semicircular and its diameter being the same as the exterior diameter of the hub-flange 30, carried by the eccentric sheave 24, so that the handle-spindle 22 and the hub-flange 30 project through the slot 29, and the 65 latch-piece has a certain reciprocation thereon equal in extent to its throw when reciprocated as a lock.

At each end of the rectangular extension or frame 28 are formed two lateral flanged lugs 31, which extend across from top to bottom 70 and contain between them the sheave 24, the distance between the inner faces of these two lugs being exactly equal to the diameter of the sheave. Each of the lugs 31 is transversely slotted in the center, as shown at 32, 75 and in the slot travels a small block or tongue 33, which is longer than the thickness of the lugs 31, so as to project from the inner face of the latter when pressed inwardly by the spring 34, which is attached thereto at one 80 end and at the other end is bent back, as at 35, and inserted into an appropriate recess 36, formed in the end of each lug 31. It will thus be seen that the two tongues 33 are pressed against the face of the eccentric 85 sheave so as to drop into the notch 25 when the latter is brought opposite to one of them, as shown in Figs. 2 and 4.

The operation of the two moving parts within the case 18 will be readily understood, and these two moving parts constitute the main features of the lock-latch mechanism, which is therefore one of great simplicity. When one of the handles 37, which are carried upon the respective ends of the spindle 22 and secured thereto in any suitable manner, as by screws 38, is rotated, supposing for the moment that neither of the tongues 33 engages in the notch 25 of the sheave, the latter will cause the latch-piece to be first projected outwardly into the position shown in Fig. 2, whereby it will be caused to be locked in a socket provided for it, to be hereinafter described; but when rotated in the opposite direction the sheave will retract or draw the 100 tongue 27 into the position shown in Fig. 4, and in this position it will be seen that the rear tongue 33 will drop into the notch 25, so as to secure the latch-piece fast to the eccentric sheave, and thereby to the handle-spindle, and the further rotation of the handle-spindle in the proper direction will now cause the latch-piece to be rotated about the handle-spindle as an axis into the position shown in dotted lines in Fig. 4, this rotation being 105 enabled by the slot 39 in the side face of the lock-casing being made of extra width for this purpose, as shown in Fig. 4, and the rotation of the latch-piece in this manner will cause a disengagement of the tongue 27 from 110 the catch-dog, to be presently described.

The catch-piece which I use to coöperate with the tongue 27 is a compound catch and bolt-socket corresponding to the compound nature of the lock, and it is shown in detail 115 in Fig. 10. This catch-piece is of improved form, having the base-plate 40 provided with a rectangularly-extending flange or edge plate 41, which is adapted to extend over the edge of the door-jamb and to be mortised 120 thereinto and to be secured by screws or other fastenings passing through holes 42, formed transversely in the plate 41, while the base-plate 40 may be likewise provided with addi-

tional screw-holes 43 for the insertion of screws 44. Projecting from the front of the base-plate 40 and close to the edge of the door-jamb is the catch 45, which is of the ordinary type, having an upper oblique cam-face 46, adapted to catch and raise the latch when the door is being closed, and a shoulder or dog 47, adapted to catch and hold the tongue 27 when it drops therewith, and is supported upon a seat 48, which is on a level with the lower edge 49 of the slot 39 in the lock-casing. The plate 40 has also projecting therefrom, just back of the catch 45 and preferably formed integrally with said plate, a bolt-socket 50, which is adapted to receive the end of the tongue 27 when shot therewith by the rotation of the sheave 24, as just described, and to this end the upper edge 51 of the socket is so positioned that the tongue 27 will be confined thereby when projected into said socket and prevented from rising from its seat 48 upon the catch 45, thus preventing the rotation of the tongue when in its locked position, so that the cover of the socket 50 and the dog 47 act simultaneously to prevent the opening of the door by pressure from the rear or outer side thereof.

Describing now the casing 16 of the lock, this is shown in detail in Fig. 6. From that figure it will be seen that the edge piece 52 is prolonged into an edge plate or flange 53, adapted to overlie and to be mortised into the edge of the door in the same way as the flange 41 overlies the edge of the door-jamb, and it is similarly adapted to be attached to the edge of the door by screws inserted through holes 54, whereby the attachment of the lock to the door is very greatly strengthened and the fastening is prevented from being torn off by any ordinary means. The mode of attachment of the cover-plate 17 to the inner face of the casing 16 consists in a pair of snugs 55, which are formed on the edge adjacent to the plate 53 and are adapted to fit into corresponding recesses 56, formed in the plate 53. On the opposite side of the cover-plate and centrally thereof is provided a screw-hole 57, through which is passed a screw 58, and is embedded in a suitable female-threaded screw-lug 59, cast upon the side 19 of the box 16, and in order to further secure the cover-plate against displacement I may provide suitable snugs 60, projecting from the interior face of the cover-plate and abutting against the inner faces of the sides 18 and 19 of the box 16, so that when the snugs 55 are inserted into the recesses 56 provided for them and the screw 58 inserted in its socket the cover-plate will be firmly secured against disturbance.

I will now describe the method by which the tongues 33 are released from the notch 25 when engaged therewith in order to lock or unlock the door. As will be seen from Figs. 2 to 5 and Fig. 8, the handle-spindle 22 is made in the form of a cylindrical barrel, and mounted centrally within the spindle 22 there

is a locking-barrel 61, which is of external diameter the same as the internal diameter of the spindle 22, so that it may be inserted and held against lost motion therein. The locking-barrel 61 is prevented from turning within the spindle 22 by a releasing-bolt 62, which is secured to a part thereof and projects outwardly through an aperture 63 in the spindle and through a socket 64, formed longitudinally through the center of the eccentric sheave, the axis of this socket being coincident with the diameter common to the center of the spindle 22 and the notch 25, so that the releasing-bolt is adapted to be projected forwardly in its socket and into the notch 25, as shown in Fig. 3, to raise the tongue 33 out of said notch, whereby the eccentric sheave may be turned.

The locking-barrel 61 is formed at either end of the same diameter as the inner diameter of the spindle 22, as hereinbefore mentioned; but it has between the two ends thereof and close to that end which is on the inside of the door—that is to say, on the side on which the casing of the lock is attached—an annularly-reduced portion 65, and from this annularly-reduced portion 65 a segment upon one side is cut away, the recess thus formed being adapted to be filled by a segmental block 66 of shape corresponding to the cut-away portion and having on its extremities a pair of projecting lugs 67, adapted to reciprocate within two radial slots 68, formed on the respective flanks or shoulders of the reduced portion 65, as clearly shown in Fig. 11.

Through the center of the locking-barrel 61 is formed an axial bore 69, and this bore is hollowed or scooped out opposite the segmental recess in the reduced portion 65 through an arc slightly exceeding a semicircle, as clearly shown at 70 in Figs. 2, 3, and 4, thus forming a recess for the operating-feather 71 upon the end of the shank 72 of the key 73. The segmental block 66 has in its outer face a screw-threaded socket 74, into which is screwed a stud 75, which is formed on the end of the releasing-bolt 62, this stud 75 being of smaller diameter than the bolt 62, so as to form a shoulder 76 at the inner end of the bolt, and between this shoulder and the face of the block 66 is secured a circular plate-spring 77, which is adapted to lie in the annular recess 65 and to embrace the barrel 61 and block 66, so as to hold them together, and in the center of the spring 77 is formed a hole 78 of just sufficient diameter to fit over the stud 75, so that when the latter is screwed home the spring 77 will be firmly secured in place in the manner shown in Fig. 5. Now when the key 73 is inserted through one of the keyholes 79, formed centrally in the handles 37, and the operating-feather 71 is seated in the recess 70, by turning the key the operating-feather is caused to press the segmental block 66, so as to push it outwardly against the pressure of the spring 77 into the position shown in Fig. 3,

and thereby the releasing-bolt 62 is projected into the notch 25 and the tongue 33 is released therefrom, whereupon rotation of the handle 37 will cause the latch-tongue 27 to be shot into or withdrawn from the socket 50, as the case may be.

In order to prevent the operation of the releasing-bolt by any key that may be inserted into the lock having a proper operating-feather, I provide a locking-feather 80 upon the shank 72 of the key, this feather being located above the feather 71 and being formed, preferably, to project in both directions from the shank 72 and having steps 81 symmetrically formed on the two opposite halves of the feather and adapted to coöperate with similarly-formed grooves or wards 82, formed within the locking-barrel 61 at the end thereof opposite to the recess 65, and in order to enable the insertion of the key in the barrel the bore 69 is widened out into a diametrical slot of sufficient width for the widest part of the two feathers 71 and 80 to pass therethrough, as will be well understood. That end of the locking-barrel adjacent to the inner handle 37 is not provided with grooves or wards 82, because ordinarily it will not be desired to prevent people from opening the door from the inside, so that such provision will be unnecessary.

When the key 73 is inserted through the keyhole 79 in the handle and into the locking-barrel 61 and is brought to its seat by any suitable contrivance—as, for instance, by a shoulder 83, formed on the base of the feather 80—the steps 81 will then mesh with the corresponding grooves 82, and the key may be turned so as to press the segmental block 66 upwardly and release one of the tongues 33 from the notch 25, when, supposing the bolt to be shot and the apparatus in the position shown in Fig. 3, the handle may be rotated in either direction through a half-revolution until the notch 25 comes opposite the other tongue 33, which will thereupon drop therewith, the segmental block and releasing-bolt having been meanwhile snapped back into place by the slight overturning of the key. When in this position, (shown in Fig. 4,) the latch-tongue will be engaged with the catch-dog 47 and may be released therefrom by slightly rotating the handle to the left, when the parts will assume the positions shown in dotted lines in Fig. 4. In shooting the bolt 27 to lock the door the same operation of inserting and turning the key will be performed and the handle will be again rotated a half-revolution in either direction until the forward tongue 33 snaps into the notch 25, when the projection of the tongue 27 into the socket 50 will prevent the handle 37 from being further turned in either direction until the key is again brought into service.

As a slight modification of the releasing-bolt mechanism shown in Figs. 5 and 11, I provide that shown in Fig. 15, wherein the bottom of the reduced portion 65 is provided with

two lateral grooves 65^a, and the segmental block 66', corresponding to the block 66, has corresponding grooves 65^b formed around the ends thereof, and in these grooves are seated a pair of circular springs 77' of the same form as the spring 77, only narrower, these springs 77' being adapted to take the place of the spring 77, as will be seen. However, the cylindrical barrel-releasing mechanism shown in Figs. 11 and 15 is by no means essential to the operation of my invention, for I may substitute other means for reciprocating the bolt 62 than that herein shown, the locking-barrel mechanism shown being simply that preferably used by me in the present form of the device.

In cases where very heavy doors are to be locked and correspondingly-heavy bolts are required—as, for instance, in store-room, magazine, or safe doors—I may provide the special form of latch-lock shown in Figs. 13 and 14, and this form comprises a plurality of locking-bolts, only one of which is adapted to act as a latch-tongue in the manner hereinbefore described and all of which are arranged to be shot and drawn simultaneously with said latch-tongue. In these figures the casing of the lock is designated by the numeral 16', and it has screw-fastenings 20 and a screw-lug 59' of precisely the same nature as the fastenings 20 and the lug 59 in the first form described. The hollow handle-spindle 22, carrying the notched eccentric sheave 24, and the releasing-bolt mechanism carried thereby are of precisely the same form as those before described; but the latch-piece 26' is of slightly-different form, having the rectangular frame 28' thereof formed to coöperate with the larger rectangular bolt-frame 84. This bolt-frame 84 is formed, as shown, of two reciprocating bolts 85, respectively above and below the central latch-piece and connecting tenons 86 at the front and rear of the rectangular frame 28' of the said latch-piece. This frame 84 is guided to reciprocate back and forth horizontally by suitable snugs 88^a, projecting from the inner face of the cover-plate 17', and to cause this reciprocation the tenons 86 are adapted to have contact with the edges of the frame 28', each tenon 86 carrying a pair of friction-rollers 87 on inwardly-projecting bearing-lugs 88 formed thereon. The rollers 87 roll upon the outer edge 89 of the frame 28', this edge being formed circular and concentric with the axis of the handle-spindle 22, so that when the latch-tongue 27 is withdrawn and turned to act as a latch this will occur without any movement of the bolt-frame 84, as clearly indicated by the dotted lines. It will thus be seen that while the reciprocation of the latch-piece 26' will cause the simultaneous reciprocation in the same direction of the bolts 85, yet the tongue 27 can be readily raised and lowered in its withdrawn position without in any way affecting the movement of the bolts 85. On the contrary, these will be held in withdrawn posi-

tion and with their faced ends flush with the edge-plate 52' of the box 16' of the lock. Corresponding with this modified form of lock-latch, I provide a similarly-modified 5 form of catch-piece, the base-plate 40' of which is extended to the length of that of the box 16', and it has three sockets therein, (numbered, respectively, 50', 50^a, and 50^b,) the first being arranged to act in conjunction 10 with the catch 45', as before described, while the two side sockets 50^a and 50^b are close to the edge of the door-jamb and positioned to receive the ends of the bolts 85, as shown in Fig. 13. The catch-piece may be secured to the door 15 by means of suitable screws 44', and it is otherwise formed, preferably, in a similar manner to the catch-piece shown in Fig. 10.

The advantages presented by my improved latch-lock will be obvious to all in that they 20 not simply dispense with unnecessary parts and greatly contract the size of the door-fastening, but also provide a rapid and ready means for unlocking the door by a single handle, and it will be observed that after the 25 key has released the tongue from the eccentric sheave and the latter has been turned slightly a further rotation of the key will cause the barrel and the handle itself to rotate, so that all that will be necessary will 30 be simply to turn the key, as the friction of the key-feather 71 upon the interior of the segmental block 66 will generally suffice to turn the eccentric sheave out of engagement with the tongue 33 when the latter has once 35 been pushed out of its seat in the notch. A further advantage is that the time lost in searching for a keyhole in the dark or in trying to insert the key into the keyhole of an ordinary lock is minimized, because the key- 40 hole in my lock-latch being precisely in the center of the handle it can be found at once by the sense of touch and without it being necessary to see where the keyhole is. In the modified form used for heavy doors the 45 advantage of having a simple latch and a compound lock both operated by the same handle will be apparent in that it decreases the strength necessary to operate the latch and provides a latch-fastening mechanism 50 not ordinarily present on such doors, which are in general provided simply with bolts.

While I have shown in the accompanying drawings the preferred form of my invention, it will be understood that I do not limit myself to the precise form shown, for many of the details may be changed in form or position without affecting the operativeness or utility of my invention, and I therefore reserve the right to make such modifications as 55 are included in the scope of the following claims.

Having thus described my invention, what I claim as new, and desire to secure by Letters Patent, is—

65 1. A lock-latch comprising a reciprocable oscillable latch-piece, a rotatable handle-spindle at right angles thereto, and means carried

by said handle-spindle and rotating therewith and adapted to engage at one point of its revolution with said latch-piece to oscillate the 70 same in a vertical plane about its own axis and at other points in its revolution to engage said latch-piece to reciprocate the same in a horizontal line.

2. A lock-latch comprising a reciprocable 75 oscillable latch-piece, a rotatable handle-spindle at right angles thereto, and means carried by said handle-spindle and rotating therewith and adapted to engage at one point of its revolution with said latch-piece to oscillate the 80 same in a vertical plane about its own axis and at other points in its revolution to engage said latch-piece to reciprocate the same in a horizontal line, said means being adapted to engage with said latch-piece at the opposite 85 point of its revolution from the first-named point so as to hold the said handle-spindle against rotation.

3. A lock-latch comprising a reciprocable 90 oscillable latch-piece, a rotatable handle-spindle at right angles thereto, means carried by said handle-spindle and rotating therewith and adapted to engage at one point of its revolution with said latch-piece to oscillate the 95 same in a vertical plane about its own axis and at other points in its revolution to engage said latch-piece to reciprocate the same in a horizontal line, said means being adapted to engage with said latch-piece at the opposite 100 point of its revolution from the first-named point so as to hold the said handle-spindle against rotation, and key-operated means for releasing said handle-spindle to enable it to be turned.

4. A lock-latch comprising a reciprocable 105 oscillable tongue carrying a slotted frame or extension, a rotatable handle-spindle passing through the slot thereof, and an eccentric disk carried by said spindle adapted to engage between side flanges carried by said extension to reciprocate said tongue, and means for independently oscillating said tongue.

5. A lock-latch comprising a reciprocable 115 oscillable tongue carrying a slotted extension, a handle-spindle projecting through the slot thereof, and an eccentric disk carried by said handle-spindle and engaging between side flanges carried on said extension, said disk having a notch therein adapted to be engaged at a certain point of its revolution by a projecting tongue carried by said extension.

6. A lock-latch comprising a reciprocable 125 oscillable tongue carrying a slotted extension, a handle-spindle projecting through the slot thereof, an eccentric disk carried by said handle-spindle and engaging between side flanges carried on said extension, said disk having a notch therein adapted to be engaged at a certain point of its revolution by a projecting tongue carried by said extension, and key-operated means for releasing said tongue from the notch of said disk.

7. A lock-latch comprising a reciprocable 130 oscillable latch-tongue having a slotted

flanged extension, a handle-spindle projecting through the slot thereof, an eccentric disk having a notch in its periphery carried by said handle-spindle and engaged between 5 the flanges of said extension, and a spring-pressed tongue-piece carried by said extension and adapted to project into said notch.

8. A lock-latch comprising a reciprocable oscillable latch-tongue having a slotted 10 flanged extension, a handle-spindle projecting through the slot thereof, an eccentric disk having a notch in its periphery carried by said handle-spindle and engaged between 15 the flanges of said extension, a spring-pressed tongue-piece carried by said extension and adapted to project into said notch, and a key-operated releasing-bolt adapted to disengage said tongue-piece from said notch.

9. In a lock-latch, the combination of a reciprocable oscillable latch-tongue, a handle-spindle connected therewith, a handle mounted on said spindle, means connected with said spindle for reciprocating said latch-tongue as a locking-bolt, means for locking it to the 25 handle-spindle to oscillate therewith as a latch, means for locking the handle-spindle against rotation when said tongue is in shot position, and key-operated means for releasing said handle when locked against rotation 30 and also when locked to the latch-tongue to oscillate the same.

10. In a lock-latch, the combination of a reciprocable oscillable latch-tongue, a handle-spindle connected therewith, a handle mounted 35 on said spindle, means connected with said spindle for reciprocating said latch-tongue as a locking-bolt, means for locking it to the handle-spindle to oscillate therewith as a latch, means for locking the handle-spindle 40 against rotation when said tongue is in shot position, and key-operated means for releasing said handle when locked against rotation and also when locked to the latch-tongue to oscillate the same, said means being contained 45 within the barrel of the spindle.

11. A lock-latch comprising a reciprocable oscillable latch-tongue having a rectangular slotted extension, lateral flanges formed upon the ends of said extension, a hollow handle-spindle projecting through the slot thereof, 50 an eccentric disk carried by said spindle and adapted to rotate between the flanges of said extension to reciprocate said latch-tongue, said eccentric disk having a notch in its periphery, a spring-operated tongue mounted 55 upon said extension and adapted to engage in said notch, a releasing-bolt extending radially from the interior of the handle-spindle to said notch to release said tongue therefrom, and 60 key-operated means within the handle-spindle for causing the reciprocation of said bolt to release said tongue.

12. A lock-latch comprising a reciprocable oscillable latch-tongue having a rectangular 65 slotted extension, a pair of lateral flanges projecting from opposite sides of said extension, a pair of spring-pressed tongue-pieces adapted

to project inwardly through the opposed sides of said flanges, a hollow cylindrical handle-spindle projecting through the slot of said extension, and an eccentric disk carried by said handle-spindle and engaging said lateral flanges, said disk having a notch in its periphery into which either of said tongue-pieces is adapted to be projected to lock the 70 handle against rotation in the one case and to provide for the oscillation of the latch-tongue in the other.

13. A lock-latch comprising a reciprocable oscillable latch-tongue having a rectangular slotted extension, a pair of lateral flanges projecting from opposite sides of said extension, a pair of spring-pressed tongue-pieces adapted 75 to project inwardly through the opposed sides of said flanges, a hollow cylindrical handle-spindle projecting through the slot of said extension, an eccentric disk carried by said handle-spindle and engaging said lateral flanges, said disk having a notch in its periphery into which either of said tongue-pieces is adapted to be projected to lock the 80 handle against rotation in the one case and to provide for the oscillation of the latch-tongue in the other, and key-operated means within the barrel of the spindle for releasing 85 said tongue-piece from said notch.

14. A lock-latch comprising a reciprocable oscillable latch-tongue having a rectangular slotted extension, a pair of lateral flanges projecting from opposite sides of said extension, a pair of spring-pressed tongue-pieces adapted 90 to project inwardly through the opposed sides of said flanges, a hollow cylindrical handle-spindle projecting through the slot of said extension, an eccentric disk carried by said 95 handle-spindle and engaging said lateral flanges, said disk having a notch in its periphery into which either of said tongue-pieces is adapted to be projected to lock the handle against rotation in the one case and to provide for the oscillation of the latch-tongue in the other, and key-operated means within the barrel of the spindle for releasing 100 said tongue-piece from said notch.

15. A lock-latch comprising a reciprocable oscillable latch-tongue having a rectangular slotted extension, a pair of lateral flanges projecting from opposite sides of said extension, 105

a pair of spring-pressed tongue-pieces adapted to project inwardly through the opposed sides of said flanges, a hollow cylindrical handle-spindle projecting through the slot of said extension, an eccentric disk carried by said handle-spindle and engaging said lateral flanges, said disk having a notch in its periphery into which either of said tongue-pieces is adapted to be projected to lock the 110 handle against rotation in the one case and to provide for the oscillation of the latch-tongue in the other, a reciprocating releasing-bolt contained within said disk and adapted to be projected into the notch thereof, and key-operated means within the barrel of said 115 handle-spindle for projecting said bolt into said notch.

15. A lock-latch comprising a reciprocable oscillable latch-tongue having a rectangular slotted extension, a pair of lateral flanges projecting from opposite sides of said extension, 120 a pair of spring-pressed tongue-pieces adapted to project inwardly through the opposed sides of said flanges, a hollow cylindrical handle-spindle projecting through the slot of said extension, an eccentric disk carried by said handle-spindle and engaging said lateral flanges, said disk having a notch in its periphery into which either of said tongue-pieces is adapted to be projected to lock the handle 125 against rotation in the one case and to provide for the oscillation of the latch-tongue in the other, a reciprocating releasing-bolt contained within said disk and adapted to be 130

projected into the notch thereof, key-operated means within the barrel of said handle-spindle for projecting said bolt into said notch, and a spring operating upon said bolt to hold it in retracted position.

16. A lock-latch comprising a reciprocable oscillable latch-tongue having a rectangular slotted extension, a pair of lateral flanges projecting from opposite sides of said extension, 10 a pair of spring-pressed tongue-pieces adapted to project inwardly through the opposed sides of said flanges, a hollow cylindrical handle-spindle projecting through the slot of said extension, an eccentric disk carried by said handle-spindle and engaging said lateral flanges, said disk having a notch in its periphery into which either of said tongue-pieces is adapted to be projected to lock the handle against rotation in the one case and to provide 15 for the oscillation of the latch-tongue in the other, a releasing-bolt mounted in a radial bore in said disk and adapted to be projected into said notch, a locking-barrel contained within said hollow spindle, and a segmental 20 block to which the inner end of said releasing-bolt is secured, said block being adapted to be projected outwardly by a key.

17. A lock-latch comprising a reciprocable oscillable latch-tongue having a rectangular slotted extension, a pair of lateral flanges projecting from opposite sides of said extension, 30 a pair of spring-pressed tongue-pieces adapted to project inwardly through the opposed sides of said flanges, a hollow cylindrical handle-spindle projecting through the slot of said extension, an eccentric disk carried by said handle-spindle and engaging said lateral flanges, said disk having a notch in its periphery into which either of said tongue-pieces is 35 adapted to be projected to lock the handle against rotation in the one case and to provide for the oscillation of the latch-tongue in the other, a releasing-bolt mounted in a radial bore in said disk and adapted to be projected into said notch, a locking-barrel contained within said hollow spindle, a segmental 40 block to which the inner end of said releasing-bolt is secured, said block being adapted to be projected outwardly by a key, and a circular 45 spring-plate embracing said segmental block and locking-barrel whereby to hold said releasing-bolt in retracted position.

18. In a lock, the combination of a releasing-bolt, a locking-barrel mounted opposite 50 the inner end of the bolt, a segmental block seated in a recess in said barrel and adapted to be operated by a key and to which the inner end of said bolt is secured, and a piece having a socket in which said releasing-bolt 55 slides and adapted to release a tongue or block 33 whereby the parts locked by the block 33 can be moved.

19. In a lock, the combination of a releasing-bolt, a locking-barrel mounted opposite 60 the inner end of the bolt, a segmental block seated in a recess in said barrel and adapted to be operated by a key and to which the in-

ner end of said bolt is secured, a spring adapted to hold said bolt in retracted position against the operation of a key, and a piece 70 having a socket in which said releasing-bolt slides and adapted to release a tongue or block 33 whereby the parts locked by the block 33 can be moved.

20. In a lock, the combination of a locking-barrel having an aperture for a key, a segmental block mounted in a recess in said locking-barrel and adapted to be pressed outwardly by the feather of the key, a releasing-bolt mounted at one end upon said segmental 75 block, a circular spring embracing said segmental block and locking-barrel whereby to hold the same together against the operation of the key, and a piece having a socket in which said releasing-bolt slides and adapted to release a tongue or block 33 whereby the parts locked by the block 33 can be moved.

21. In a lock, the combination of a locking-barrel having an annularly-reduced portion and a segmental recess therein, a segmental 90 block seated in said recess and having a pair of lateral lugs 67 adapted to slide in grooves formed in the ends of said recess, a releasing-bolt having a screw-threaded stud socketed in a threaded aperture in said segmental block, 95 a circular spring-plate having a hole therethrough, through which said stud is passed, whereby to secure said spring-plate between the shoulder of said bolt and said segmental block, and a piece having a socket in which 100 said releasing-bolt slides and adapted to release a tongue or block 33 whereby the parts locked by the block 33 can be moved.

22. In a lock, the combination of a locking-barrel having an annularly-reduced portion 105 and a segmental recess therein, a segmental block seated in said recess and having a pair of lateral lugs 67 adapted to slide in grooves formed in the ends of said recess, a releasing-bolt having a screw-threaded stud socketed 110 in a threaded aperture in said segmental block, a circular spring-plate having a hole therethrough, through which said stud is passed, whereby to secure said spring-plate between the shoulder of said bolt and said 115 segmental block, a series of wards or grooves formed within the bore of said locking-barrel and adapted to be engaged by similarly-formed notches on the feather of the key, and a piece having a socket in which said 120 releasing-bolt slides and adapted to release a tongue or block 33 whereby the parts locked by the block 33 can be moved.

23. A lock-latch comprising a box or case, a latch-tongue having a rectangular slotted extension adapted to reciprocate longitudinally in said case and also to oscillate therein and to project through a slot in the front edge thereof, a handle-spindle projecting transversely through said case and through the slot 130 of said extension, and means carried by said handle for reciprocating and oscillating said latch-tongue, in combination with a catch-piece having a catch-dog adapted to retain

the lower edge of said tongue when used as a latch, and a projection adapted to form an abutment for the upper edge of said tongue to prevent it from being rotated when projected forward as a lock.

24. A compound lock-latch comprising a reciprocal oscillable latch-tongue, means for oscillating said tongue as a latch, means for shooting and drawing said tongue as a bolt, and one or more subsidiary bolts engaging with said latch-tongue to be shot or drawn therewith in its reciprocating movements.

25. A compound lock-latch comprising a reciprocal oscillable latch-tongue, means for oscillating said tongue as a latch, means for shooting and drawing said tongue as a bolt, and one or more subsidiary bolts engaging with said latch-tongue to be shot or drawn therewith in its reciprocating movements, said subsidiary bolts being adapted to remain stationary when said tongue is oscillated as a latch.

26. A compound lock-latch comprising a reciprocal oscillable latch-tongue carrying an extension or frame thereon, a handle-bar passing transverse to said latch-tongue and adapted to reciprocate the same as a lock or to oscillate the same as a latch, a bolt-frame comprising reciprocating bolts located on opposite sides of said latch-tongue and tenons connecting the same, said tenons being caused to engage with the sides of said extension, whereby the reciprocation of said tongue is adapted to reciprocate said bolt-frame.

27. A compound lock-latch comprising a reciprocal oscillable latch-tongue carrying an extension or frame thereon, a handle-bar passing transverse to said latch-tongue and adapted to reciprocate the same as a lock or to oscillate the same as a latch, a bolt-frame comprising reciprocating bolts located on opposite sides of said latch-tongue and tenons connecting the same, said tenons being caused to engage with the sides of said extension, whereby the reciprocation of said tongue is adapted to reciprocate said bolt-frame, said extension being formed with circular concentric faces, whereby the oscillation of said latch-tongue may take place while retaining said bolt-frame in stationary position.

28. A compound lock-latch comprising a reciprocal oscillable latch-tongue, means for oscillating said tongue as a latch, means for reciprocating said tongue as a lock, and one or more subsidiary bolts engaging with suitable projections formed on said tongue whereby they are reciprocated therewith, in combination with a catch-piece having a base-plate, a catch formed thereon having a dog adapted to engage said latch-tongue, a bolt-socket formed rearwardly of said catch to engage said bolt-tongue when it is projected as a lock, and one or more subsidiary bolt-sockets adapted to engage said subsidiary bolt or bolts located adjacent to the edge of the door frame.

29. A compound lock-latch comprising a re-

ciproable oscillable latch-tongue having a slotted extension formed rearwardly thereof, a handle-spindle adapted to project through the slot thereof, an eccentric disk carried on said spindle, a pair of lateral flanges formed upon said extension and engaging said eccentric disk on either side thereof, the edges of said extension being formed concentric with said handle when the tongue is in position for oscillation as a latch, and a bolt-frame surrounding said extension and carrying one or more subsidiary bolts, and having points adapted to engage said concentric edges of said extension, whereby said tongue is adapted to hold said bolt-frame stationary during its oscillating movements, and to reciprocate the same during its reciprocating movements.

30. A compound lock-latch comprising a reciprocal oscillable latch-tongue having a slotted extension formed rearwardly thereof, a handle-spindle adapted to project through the slot thereof, an eccentric disk carried on said spindle, a pair of lateral flanges formed upon said extension and engaging said eccentric disk on either side thereof, the edges of said extension being formed concentric with said handle when the tongue is in position for oscillation as a latch, a bolt-frame surrounding said extension and carrying one or more subsidiary bolts and having points adapted to engage said concentric edges of said extension, whereby said tongue is adapted to hold said bolt-frame stationary during its oscillating movements and to reciprocate the same during its reciprocating movements, means for locking said latch-tongue to the handle-spindle when in retracted position, whereby said latch-tongue is oscillated by the spindle, and means for locking said handle-spindle to said latch-tongue when the latter is in projected position to prevent the rotation of the spindle and the withdrawal of said tongue.

31. A compound lock-latch comprising a reciprocal oscillable latch-tongue having a slotted extension formed rearwardly thereof, a handle-spindle adapted to project through the slot thereof, an eccentric disk carried on said spindle, a pair of lateral flanges formed upon said extension and engaging said eccentric disk on either side thereof, the edges of said extension being formed concentric with said handle when the tongue is in position for oscillation as a latch, a bolt-frame surrounding said extension and carrying one or more subsidiary bolts and having points adapted to engage said concentric edges of said extension, whereby said tongue is adapted to hold said bolt-frame stationary during its oscillating movements and to reciprocate the same during its reciprocating movements, means for locking said latch-tongue to the handle-spindle when in retracted position, whereby said latch-tongue is oscillated by the spindle, means for locking said handle-spindle to said latch-tongue when the latter is in projected position to prevent the rotation of the spindle and the withdrawal of said tongue,

and key-operated means within the handle for releasing said latch-tongue from the handle-spindle.

32. A compound lock-latch comprising a reciprocable oscillable latch-tongue having a rectangular slotted extension, a rotatable handle-spindle projecting through the slot thereof, means carried by said handle-spindle for reciprocating and also oscillating said latch-tongue, said extension having arcuate edges concentric with said handle-spindle when the latch-tongue is in retracted position, a bolt-frame surrounding said extension and comprising a pair of parallel reciprocable bolts connected by a pair of vertical tenons at opposite sides of said extension, bearing-lugs carried by said tenons, and friction-rollers mounted upon said bearing-lugs and bearing against said concentric edges.
33. A compound lock-latch comprising a reciprocable oscillable latch-tongue having a rectangular slotted extension, a rotatable handle-spindle projecting through the slot thereof, means carried by said handle-spindle for reciprocating and also oscillating said latch-tongue, said extension having arcuate edges concentric with said handle-spindle when the latch-tongue is in retracted position, a bolt-frame surrounding said extension and comprising a pair of parallel reciprocable bolts connected by a pair of vertical tenons at opposite sides of said extension, bearing-lugs carried by said tenons, friction-rollers mounted upon said bearing-lugs and bearing against said concentric edges, means for locking said handle-spindle to said latch-tongue in each of its extreme positions, and key-op-

erated means for releasing said spindle from said latch-tongue.

34. A compound lock-latch comprising a reciprocable oscillable latch-tongue having a rectangular slotted extension formed upon its rear end, a handle-spindle passing transversely through the slot thereof, an eccentric disk carried by said handle-spindle and having a notch in its periphery, a pair of lateral flanges formed on opposite sides of said rectangular extension and engaging the opposite sides of said disk, a pair of spring-pressed tongues slidably mounted in said extension and adapted to engage alternately in the notch of said disk, said flanges being formed with arcuate edges concentric with the handle-spindle when the latch-tongue is in its retracted position, a releasing-bolt slidably mounted in said disk and adapted to be projected into said notch to release the tongue therefrom, key-operated means within the handle for operating said releasing-bolt, and a bolt-frame carrying reciprocable bolts thereon parallel to said latch-tongue and adapted to be reciprocated therewith, and having projecting surfaces engaging with said concentric edges, whereby the latch-tongue may be oscillated as a latch while holding said bolt-frame stationary but causing the latter to be reciprocated with it as a lock, substantially as described.

In witness whereof I have hereunto set my hand in the presence of two witnesses.

MAXIME VALLÉE.
